UNITED STATES PATENT OFFICE

WILLIAM ECCARDT, OF OVERLAND, MISSOURI

DISPENSING RECEPTACLE FOR PAPER BAGS

Application filed November 4, 1931. Serial No. 573,000.

This invention relates to a dispensing receptacle for paper bags and it consists in the novel features hereinafter described and claimed.

An object of the invention is to provide a receptacle of the character stated consisting of a case having a platform member pivoted therein and adapted to support a stack of paper bags. Spring means are provided for holding the platform at an elevated position. Feeding rolls are journaled in the case and are located in advance of the forward end of the stack of bags. The uppermost bag of the stack is adapted to pass over the said feeding rolls and as one bag is withdrawn from the case, means is provided for causing the next bag in the stack to follow the preceding bag.

In the accompanying drawings:

Figure 1 is a longitudinal sectional view of the dispensing receptacle.

Figure 2 is a top plan view of the case with the cover removed.

Figure 3 is a transverse sectional view cut on the line 3—3 of Figure 1.

Figure 4 is a transverse sectional view cut on the line 4—4 of Figure 1.

As illustrated in the accompanying drawings:

The dispensing receptacle consists of a substantially rectangular case 1 provided with an open top and at one end with an outlet opening 2 and the open top is closed by a removable cover 3. The partition wall 4 is located in the case 1 and a platform member 5 is pivotally mounted in the case. A spring 6 is connected at one end with the partition wall 4 and at the other end to the lower end of a depending arm 5' that is secured to the under surface of the platform member 5. The said spring serves to hold the platform 5 under tension and in a normal horizontal plane. A stack of bags indicated at 7 is adapted to rest upon the platform member 5. A plate 8 is adjustably mounted upon the partition wall 4 and is provided with a slot 9 through which the screw 10 passes, whereby the said plate 8 may be adjusted vertically with relation to the partition wall. The forward end of the

case is provided with an opening 11, through which a screw driver (not shown) may be passed for turning the screw 10 to permit the vertical adjustment of the plate 8 and for fixing the plate with relation to the partition wall 4. Rollers 12 arranged in spaced relation with respect to each other, are secured to a shaft 11 that is journaled in brackets 12' fixed to and rising from the upper edge of the plate 8, and the said rollers are located in advance of the forward end of the stack of bags 7. The top bag upon the stack may pass over the rollers 12 but the lower bags of the stack are held from forward movement between said rollers. A roller 13 is arranged in advance of and overlaps the edges of the rollers 12 by having its periphery disposed in the space between the rollers 12 and the said roller 13 is mounted upon a shaft 14 having its ends journaled in guides 15, mounted to the inner surfaces of the sides of the case 1. Discs 16 are mounted at the end portions of the shaft 14. The roller 13 and disc 16 are adapted to engage the under surface of the top bag as it moves out of the case through the opening 2. Journalized above the shaft 14 and removably received in bearing brackets 15' is a shaft 14' that has centrally secured thereto a roller 13' which cooperates with the roller 13 and the shaft 14' has also secured thereto discs 16' that cooperate with the discs 16. The roller 13' and the discs 16' engage the upper surface of the bag as it moves out of the case 1 as indicated in Figure 1 of the drawings. Arms 17 are pivoted upon the shaft 14' and a shaft 18 is journaled in the free ends of the arms 17. The sprocket wheel 19 is mounted upon the shaft 18 and a sprocket wheel 20 is mounted upon the shaft 14'. A sprocket chain 21 is trained around the sprocket wheels 19 and 20. When the shaft 14' is turned by a bag moving between the rollers 13 and 13' and discs 16 and 16', rotary movement is transmitted by the said sprocket wheels and chain to the shaft 18. Rollers 22 are fixed to the shaft 18 and are adapted to engage the upper surfaces of the uppermost bag of the stack 7. Spring arms 23 are attached to the

sides of the arms 17 and a guide plate 24 is carried by the spring arms 23 and bears upon the upper surface of the top bag of the stack.

5 The bags are held in place on the platform 5 by the weight of the frame which include the arms 17, shaft 18 and rollers 22 and spring catches 17' are provided for holding the arms 17 and their respective rollers from 10 moving upwardly by the action of the platform. It will be noted that the catches 17' have one of their ends fixed to the arms 17 and arranged in the catches adjacent to the rear or free ends thereof are openings 15 to receive studs 18' that are formed on lugs 19' the latter being secured to and extending inwardly from the sides of the case 1 as best shown in Figure 4. The lugs have their inner ends beveled to the studs 18' to facilitate 20 the application of the catches 17' to the studs. The catches may be manually disconnected when it is desired to swing the arms 17 upwardly.

In the use of the device the cover 3 is removed from the case 1 and the shaft 18 is 25 swung to the position as shown in dotted lines in Figure 1 of the drawings. A stack of bags 7 is then placed upon the platform 5 and the shaft 18 is swung down so that the 30 rollers 22 are in contact with the upper surface of the top bag of the stack. The operator then turns the disc 16' whereby the rollers 13' and 22 are rotated and the top bag of the stack is moved thereby between 35 the guide 24 and the rollers 12 and then between the discs and rollers 13' and 13, so that the end of the bag passes through the opening 2. The cover 3 is then placed upon the case and when it is desired to withdraw a 40 bag, that end portion of the bag which is extended through the opening 2 is grasped and the bag is pulled away from the case. As the bag goes between the discs 16 and 16' and the rollers 13 and 13', the shaft 14' 45 is rotated, whereby the rollers 22 are rotated and as the uppermost bag leaves the case through the opening 2, the next bag at the top of the stack is moved forwardly to project through the opening 2.

50 Having described the invention what is claimed is:

1. In a dispensing device, a case having an

opening, a spring pressed platform pivotally mounted in the case to receive articles to be dispensed through the opening, a pair of superimposed shafts journaled in said case, 70 rollers and discs secured to said shafts and the rollers and discs of one shaft cooperating with the rollers and discs of the other shaft to receive the articles between the same when being dispensed, a frame including a pair of arms having one of their ends pivoted to the upper shaft, a shaft journaled in the other end of the arms, discs secured to the last mentioned shaft and engageable with the uppermost one of said articles to act as a weight for the articles and for disposing them in dispensing position, and means to rotate the last mentioned shaft from the upper shaft to move the articles to dispensing position through the opening. 75

2. In a dispensing device, a case having an open top and an opening in one end wall thereof, a removable cover for said open top, a spring pressed platform pivotally mounted in said case to receive articles to be dispensed through the opening, guide 80 means including rollers to guide the articles to dispensing position, a pair of superimposed shafts journaled in said case, rollers and discs secured to said shafts and the rollers and discs of one shaft cooperating 85 with the rollers and discs of the other shaft to receive the articles between the same when being dispensed, a frame including a pair of arms having one of their ends pivoted to the upper shaft, a shaft journaled in the other end of the arms, discs secured to the last mentioned shaft and engageable with the uppermost one of said articles to act as a weight for the articles and for disposing the same in dispensing position, 90 means to rotate the last mentioned shaft from the upper shaft to move the articles to dispensing position through the opening, 95 spring means secured to the arms to hold the frame in operative position with the last mentioned discs engaging the uppermost article, and latching means for the spring means whereby they can be released to allow the frame to be moved to an inoperative 100 position. 105
